SLIDE BUCKLE

Harold J. Reiter, Chicago, Ill.

Application November 12, 1947, Serial No. 142,484

Term of patent 7 years

(Cl. D17—9)

To all whom it may concern:

Be it known that I, Harold J. Reiter, a citizen of the United States of America and resident of Chicago, in the county of Cook and State of Illinois, have invented a new, original, and ornamental Design for a Slide Buckle, of which the following is a specification, reference being had to the accompanying drawing, forming a part thereof.

Fig. 1 is a top plan view of a slide buckle showing my new design.

Fig. 2 is an end elevational view thereof.

The dominant features of the design are shown in full lines.

I claim:

The ornamental design for a slide buckle, substantially as shown and described.

HAROLD J. REITTER.
